DESIGN.

—o—

G. S. HENSEL, L. D. VALETTON & F. E. COOK.

FRINGE.

No. 18,464.

Patented July 17, 1888.

UNITED STATES PATENT OFFICE.

GEORGE S. HENSEL, LOUIS D. VALETTON, AND FRANK E. COOK, OF PHILADELPHIA, PENNSYLVANIA, ASSIGNORS TO THE HENSEL, COLLADAY COMPANY, OF SAME PLACE.

DESIGN FOR A FRINGE.

SPECIFICATION forming part of Design No. 18,464, dated July 17, 1888.

Application filed April 28, 1888. Serial No. 272,211. Term of patent 7 years.

To all whom it may concern:

Be it known that we, GEORGE S. HENSEL, LOUIS D. VALETTON, and FRANK E. COOK, citizens of the United States, residing in the city and county of Philadelphia, State of Pennsylvania, have invented and produced a new and original Design for Fringes, of which the following is a specification, reference being had to the accompanying photograph, forming part thereof.

The leading features of our design for a fringe are, first, scrolls curving alternately in opposite directions with bulbs on the head thereof, and, next, the pendants with bars joining the upper portion thereof.

In the photograph, A represents the head of a fringe, and B the pendants thereof. On the head are scrolls 1, which curve alternately

in opposite directions. On the ends of the scrolls are bulbs 2, at or about the center of the head. The upper portions of the pendants are joined by bars 3.

We claim—

A design for a fringe having a head and pendants, the head having thereon the representation of scrolls curved in opposite directions, and the pendants having connecting bars at their upper parts, substantially as shown and described.

GEO. S. HENSEL.
LOUIS D. VALETTON.
FRANK E. COOK.
